UNITED STATES PATENT OFFICE

138,800

DESIGN FOR A SLACK SUIT

Helen C. Cookman, New York, N. Y.

Application January 23, 1942, Serial No. 105,385

Term of patent 7 years

(Cl. D3—17)

To all whom it may concern:

Be it known that I, Helen C. Cookman, a citizen of the United States, residing at 48 East 66th Street, city, county, and State of New York, have invented a new, original, and ornamental Design for a Slack Suit, of which the following is a specification, reference being had to the accompanying drawing forming part thereof.

Figure 1 is a front perspective view of a slack suit showing my new design. Figure 2 is a rear perspective view of the slack suit shown in Figure 1.

I claim:

The ornamental design for a slack suit, substantially as shown.

HELEN C. COOKMAN.
